UNITED STATES PATENT OFFICE

2,245,986

ELECTRIC PLUG

Herman H. Krauss, Fremont, Ohio

Application September 25, 1939, Serial No. 296,505

5 Claims. (Cl. 200—51)

The present invention relates to electric plugs of a type provided with a pair of contact prongs adapted for forming a circuit connection with an electrical receptacle or fixture and has for its primary object to provide a plug construction for breaking the circuit with the prongs whereby to prevent the danger of a person receiving a shock by coming into contact with the exposed ends of the prongs.

A further object is to provide an electric plug of this character of simple and practical construction, which is efficient and reliable in use, relatively inexpensive to manufacture and otherwise well adapted for the purposes for which the same is intended.

Other objects and advantages reside in the details of construction as more fully hereinafter described and claimed, reference being had to the accompanying drawing forming part hereof wherein like numerals refer to like parts throughout and in which:

Figure 1 is a longitudinal sectional view and

Figure 2 is a transverse sectional view taken substantially on a line 2—2 of Fig. 1.

Referring now to the drawing in detail the numeral 5 designates the cylindrical insulated body portion of the plug within which a pair of conductors 6 are embedded having the circuit wires 7 connected thereto by means of terminals 8, the terminals and connected ends of the wires being enclosed by a cap 9 threaded on one end of the body portion 5 of the plug.

The body 5 is provided with a central opening within which is fitted a sponge rubber core 10, the conductors 6 being positioned at diametrically opposite sides of the core and exposed through lateral openings 11 extending in diametrically opposite sides of the body 5. The sponge rubber core 10 is compressed between the conductors 6 and the free end of the conductors 40 terminate short of the outer end of the sponge rubber core whereby to permit the sides of the core to bulge outwardly beyond the longitudinal plane of the conductors 6, as shown at 12.

A pair of contact prongs 13 are pivoted on pins 45 14 within the outer end of the body 5 of the plug, the pivot pins 14 being positioned slightly outwardly with respect to the bulged edges 12 of the core. The inner ends of the prongs 13 are formed with lateral inwardly extending offsets 50 15 to bear against the side of the conductors 6 to provide a circuit connection therewith. The inner ends of the prongs are also provided with insulation knobs 16 which project outwardly of the lateral openings 11.

From the foregoing it will be apparent that the inner ends 15 of the prongs will be yieldably maintained out of contacting engagement with the conductors 6 by reason of the bulging sides 12 of the sponge rubber core, as shown by the full line of Fig. 1 of the drawing and accordingly the circuit connection with the prongs will be broken. However when it is desired to insert the plug into a receptacle the knobs 16 are pressed inwardly into the position as shown by the dotted lines in Fig. 1 whereby the inner ends of the prongs will contact the conductors 6 to provide a circuit connection with the prongs.

It is believed the details of construction and manner of use of the device will be readily understood from the foregoing without further detailed explanation.

What is claimed is:

1. An electric plug comprising a rigid body portion having conductors positioned therein, a pair of prongs pivoted to said body portion and having one end movable into contacting engagement with the conductors and a yieldable solid body carried by the rigid body and compressed by the prongs when the prongs are in contacting engagement, said yieldable body being adapted to normally urge the prongs out of contacting engagement.

2. An electric plug comprising a rigid body portion having conductors positioned therein, a pair of prongs pivoted to said body portion and having one end movable into contacting engagement with the conductors, a yieldable solid body carried by the first named body and compressed by the prongs when the prongs are in contacting engagement, said yieldable body being adapted to normally urge the prongs out of contacting engagement, said yieldable body possessing insulation qualities.

3. An electric plug comprising an insulation body, a pair of conductors positioned therein in spaced relation, a sponge rubber core fitted in said body and having one end compressed between said conductors, the other end of the core protruding laterally outwardly beyond the conductors, a pair of prongs pivotally carried by the body and engageable by the bulging end of the core inwardly of the pivot of the prongs to yieldably maintain one end of the prongs out of engagement with the conductors and insulation knobs carried by the prongs for manually moving the inner ends of the prongs into contacting engagement with said conductors.

4. An electric plug comprising a rigid body having conductors positioned therein, a pair of

contacts movably carried by the body and having one end movable into contacting engagement with the conductors and a yieldable solid body having one end anchored in the first named body and having its other end free and normally compressed between said contacts to urge the same from said conductors.

5. An electric plug comprising a rigid body having conductors positioned therein, a pair of

prongs pivoted to said body and having one end movable into contacting engagement with the conductor and a yieldable solid body having one end anchored in the first named body and having its other end free and normally compressed between said prongs to urge the prongs from said conductors.
